(57) **CLAIM**

We claim the ornamental design for the bottle, as shown and described.

DESCRIPTION

FIG. 1 is a left side view of a bottle showing our new design;
FIG. 2 is a front elevation view thereof;
FIG. 3 is a back elevation view thereof;
FIG. 4 is a front perspective view thereof;
FIG. 5 is a back perspective view thereof;
FIG. 6 is a top plan view thereof; and,
FIG. 7 is a right side view thereof.

The oblique shade lines shown in the drawing views represent transparency.
All sides not shown form no part of the claimed design.
